MECHANICAL SKI TOY

Glauco Poli, Brooklyn, N. Y., assignor of one-half
to Ruth Kaplan, Brooklyn, N. Y.

Application September 12, 1947, Serial No. 773,623

3 Claims. (Cl. 46—107)

1

This invention relates to an improved self propelling figure toy.

More particularly the invention relates to a toy which is constructed so as to simulate a skier, and which moves over a horizontal or slightly inclined surface by successive movements of ground engaging poles operated by a spring operated mechanism housed in the body of the toy skier figure.

One of the objects of the invention is to provide a toy skier figure with a body which is constructed so as to simulate a skier in a normal partly crouched position. Such a skier figure is supported upon skis having a rolling action on the floor or ground and provides movable spring operated arms and poles supported thereby, which arms and poles have a repeated pushing action against the ground or other supporting surface for propelling the toy over the same in a manner strongly suggestive of the natural motion of a skier in making a rapid descent over icy ground.

Another object of the invention is the provision of a toy skier with metal skis constructed with reinforcing edge ribs providing runner edges for the skis and with wheels mounted to roll over the ground and supported by shafts engaging said edge ribs.

A still further object of the invention is the provision of a toy skier with a spring motor having a reduction gear train so arranged that its friction acts as an escapement for the unwinding of the spring motor. The toy skier is further provided with a crank arm which is connected to pivotally supported arms of the figure by means of a link so arranged that a swinging motion is imparted to the arms and to the propelling ground poles carried thereby.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view, showing the skier in motion producing position.

Fig. 2 is a partial front elevation of the skier figure, partly broken away, to illustrate the spring motor and the drive for the arm swinging shaft.

Fig. 3 is a partial side elevational view, shown partly in vertical section, illustrating the position of one of the arms and its propelling pole.

Fig. 4 is a detail enlarged sectional view of the

spring motor, showing the crank shaft and connecting pitman drive for the swinging arms.

Fig. 5 is a bottom plan view of one of the skis.

Fig. 6 is a detail enlarged sectional view, showing bearing members for the arm swing shaft, of a modified construction, taken on line 6—6 of Fig. 1, looking in the direction of the arrows.

Fig. 7 is an enlarged vertical sectional view taken on the line 7—7 of Fig. 3.

10 The self propelling toy, according to the present invention, includes a body 10 simulating the human body, and which may be constructed of any material, plastic, composition, metal or otherwise, to have legs 11, a waist 12, a head 13, and arms 14 and 14^a, which are supported on the ends of a shaft 15 to swing on the upper part of the body. The entire figure is constructed to simulate a skier in the natural position of propelling himself over the ground by pushing hand carried poles against the ground.

15 The legs 11 are shown with their upper or hip portions bent at a rearward angle to themselves, thus disposing the figure in a semi-crouching position to simulate the natural position of a skier engaged in propelling himself over the ground by the manual operation of pushing poles.

20 The feet 16 are secured by means of fasteners 17 to the skis 18 and 19. These skis are shown to be formed of plastic or sheet metal, which may be aluminum or other metal, and provided with a forward end portion 20, which is curved upwardly.

25 Each ski has two wheels 18^a mounted to turn in slots 18^b on shafts 18^c.

30 The body 10 is of hollow construction to provide a compartment in which a spring motor 21 is housed. This toy spring motor includes the metal frame 22 rotatively supporting a main spring arbor or shaft 23 which turns in bearings of the frame 22, and which shaft 23 carries the spring 24 and the drive gear 25. The drive gear 25 drives the pinion 26 of the shaft 27 which also turns in bearings of the frame 22 and is provided with a crank arm 28 on one end thereof. The shaft 27 carries a transmission gear 29 which engages the pinion 30 on the shaft 31 and this shaft 31 carries a gear 32, which drives the pinion 33 on the shaft 34. All of the shafts turn in bearings of the frame 22. The shaft 34 has a gear 34^a which drives the pinion 34^b.

35 A shaft 35 is also mounted to turn in the bearings of the frame 22, and is provided on its outer ends with squared portions 36 and 37 which project outwardly of the body 10. On 40 the end portion 36 of the shaft 35, the arm 14

45

is mounted, the same being connected thereto to swing with the shaft 35 and not upon it. On the opposite end portion 37 of the shaft 35, the arm 14^a is mounted to swing with the shaft and not independently of the shaft.

The shaft 35 is provided with a short lateral arm or lug 40 which is keyed thereto against relative turning, and the upper end of the pitman or link rod 41 is pivotally connected at 42 to said arm or lug 40. The lower end of the pitman or link rod 41 is pivotally mounted on the crank arm 28.

One outer end of the spring arbor or shaft 23 projects outwardly of the body and is squared to receive a winding key.

The arms 14 and 14^a swing against the sides of the body 10 and are wholly supported on the ends of the shaft 35, to which they are interlocked against relative turning. Each of these arms is equipped with a gloved hand 43, which is connected thereto, as by the pivot pin 44. On each hand, a pushing pole 45 is secured.

The lower end of each pushing pole is provided with a sheath 46 of leather or other frictional material. The square portions 36 and 37 of the shaft 35 are disposed in the same angular relations to each other and to the body 10, so that the lower end of one of the arms will engage the ground or floor at the same time with the lower end of the other arm. The lower ends of both poles engage the ground or floor outwardly of the outer sides of the skis, so as not to interfere with the movement of the wheel equipped skis over the ground or floor.

If desired the square portions 36 and 37 may also be disposed in different angular relations to each other so that the lower end of one arm will engage the ground or floor before the lower end of the other arm and by means of this arrangement one pole will start its pushing or propelling stroke when the other pole has reached a point nearly the limit of its own pushing stroke.

By winding the spring, energy will be stored up and the gear train will be started in motion, thereby driving the crank shaft and oscillating the rock shaft 35. To insure an easy motion to this rock shaft, metal bearings 47 are provided in the body 10 therefor. The connection between each arm and the rock shaft may include a metal sleeve 48, having an integral disc collar 48^a, by which it is interlocked or cemented to the upper end of the arm, so that the arm will not be displaced on the end of the rock shaft.

When the rock shaft 35 is oscillated by the action of the pitman or link rod 41, the square portions 36 and 37 will be swung back and forth, and as they are swung, the lower ends of the poles 45 will be forced against the ground or floor, and the toy will be propelled forwardly, thus simulating the natural movements of a skier.

While I have illustrated and described the preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

1. In a self-propelling toy having a pair of laterally spaced skis provided with wheels to

roll on a flat surface, a rigid one-piece body fixedly mounted on the skis and formed with an internal hollow, arms pivotally mounted at the sides of the body to pivot on a horizontal axis, a motor mounted within the hollow of said body, means interconnecting said arms and said motor for oscillating the arms to and fro along the sides of the body, hand members freely pivotally mounted on the free ends of said arms to pivot in a vertical plane relative to said arms, and ski poles depending rigidly from said hand members and having their free ends frictionally engaging the flat surface alongside of the skis to push the toy in a forward direction as said arms are oscillated to and fro.

2. In a self-propelling toy having a pair of laterally spaced skis provided with wheels to roll on a flat surface, a rigid one-piece body fixedly mounted on the skis and formed with an internal hollow, arms pivotally mounted at the sides of the body to pivot on a horizontal axis, a motor mounted within the hollow of said body, means interconnecting said arms and said motor for oscillating the arms to and fro along the sides of the body, hand members freely pivotally mounted on the free ends of said arms to pivot in a vertical plane relative to said arms, and ski poles depending rigidly from said hand members and having their free ends frictionally engaging the flat surface alongside of the skis to push the toy in a forward direction as said arms are oscillated to and fro, said pivotal mounting of said arms comprising a horizontal shaft rotatively extended through said body and having end portions projecting beyond the sides of said body and upon which said arms are fixedly mounted.

3. In a self-propelling toy having a pair of laterally spaced skis provided with wheels to roll on a flat surface, a rigid one-piece body fixedly mounted on the skis and formed with an internal hollow, arms pivotally mounted at the sides of the body to pivot on a horizontal axis, a motor mounted within the hollow of said body, means interconnecting said arms and said motor for oscillating the arms to and fro along the sides of the body, hand members freely pivotally mounted on the free ends of said arms to pivot in a vertical plane relative to said arms, and ski poles depending rigidly from said hand members and having their free ends frictionally engaging the flat surface alongside of the skis to push the toy in a forward direction as said arms are oscillated to and fro, said pivotal mounting of said arms comprising a horizontal shaft rotatively extended through said body and having end portions projecting beyond the sides of said body and upon which said arms are fixedly mounted, said interconnecting means comprising a driven crank extending from said motor means within said body, an arm extended radially from said shaft within said body, and a link connected between the free end of said arm and said driven crank.
